UNITED STATES PATENT OFFICE.

HENRY J. WELDON, OF NORWICH, CONNECTICUT.

BUTTON-FASTENER.

SPECIFICATION forming part of Letters Patent No. 301,414, dated July 1, 1884.

Application filed May 10, 1884. (No model.)

To all whom it may concern:

Be it known that I, HENRY J. WELDON, of 5
Norwich, in the county of New London and
State of Connecticut, have invented a new and
useful Improvement in Button-Fasteners; and
I do hereby declare that the following is a full,
clear, and exact description of the same.

My invention is an improvement in button- 10
fasteners, and, while being particularly de-
signed for shoe-buttons, is applicable also to
other classes of buttons.

The object of the invention is to provide a 15
fastener which shall be simple in construction,
cheap to manufacture, and capable of being
easily attached to any button without the aid
of any sort of machine.

The invention consists of a divided shank, 20
having screw-threaded ends adapted to a
corresponding screw-thread in a base-plate,
whereby it is connected thereto, the said shank
being previously connected with the button
25 to be secured to the shoe or other fabric by
passing one of the branches of the shank
through the loop or eye of the button.

In the accompanying drawings I have re- 30
presented my invention, Figure 1 being a per-
spective view showing the button and fastener
as connected together; Fig. 2, a side elevation
with the parts separated. Fig. 3 is a modi-
fication of the base-plate and shank. Fig. 4 is
also a modification.

In these drawings I have shown an ordinary 35
shoe-button; but I desire it to be understood
that my fastener may be applied to all kinds
and styles of buttons with equally good effect,
this style being represented merely for con-
venience. The button is marked *a*.

In carrying out my invention I form a sta- 40
ple of half wire, and screw-thread the sides of
each half, as shown at *b*. This staple may be
made of any suitable material and by any
suitable machine, it being understood that I
do not limit myself in this respect. This sta-
45
ple constitutes the shank, which I have marked
A. The button *a* is placed upon the shank,
resting in the bent portion, and the shank is
then taken in the fingers and screwed into the
internally screw-threaded socket of a base-
50
plate, *B*, this action closing the space between
the ends of the shank, compressing them with-
in the socket. They are thus tightly held
with the button in the bend, and without any
chance of its becoming detached. The base-
plate *B* is preferably formed with an ordinary

plate, *c*, and shank *d*, said shank being hollow 55
and screw-threaded, and adapted to receive
the threaded ends of the shank, as above de-
scribed. Instead, however, of the form shown
in Figs. 1 and 2, I may use the form shown in
Fig. 3, where I dispense with the shank *d* of 60
Fig. 2, and use instead simply a disk, *e*, thick-
ened at the center, and having a screw-threaded
central opening for the reception of the shank
in the manner heretofore described. By this
construction ordinary buttons may be attached 65
to any fabric very easily, and in such a man-
ner as to render detachment impossible with-
out great force.

These fasteners may be attached to the but- 70
tons and sold therewith, or they may be sold
separately and applied to buttons already in
use.

For the class of buttons which are not pro- 75
vided with eyes or loops, I propose to modify
my invention, as in Fig. 4. Here I make the
shank longer than when used with the other
forms of buttons, and pass the points thereof
through the eyes of the button, pressing the
points of the shaft together on the other side,
and then screwing them into the threaded 80
shank or disk, as before described.

Instead of having the branches of the shank
of the same length, I may, as in Fig. 3, make
one end thereof longer than the other, and of
whole wire, and slightly point the shorter end, 85
so that when the long end is screwed in a cer-
tain distance the sharpened shorter end will
also enter the threaded disk sufficient to hold
the parts of the shank together.

I do not limit myself to a shank made in 90
one piece and threaded, as described, as the
parts thereof may be hinged or secured to-
gether in any suitable manner.

Having thus described my invention, what 95
I claim as new, and desire to secure by Let-
ters Patent, is—

A button-fastener consisting of a base- 100
plate having a screw-threaded opening, and a
divided shank adapted to receive and hold the
button and to be screwed into said base-plate,
substantially as described.

In testimony whereof I have signed my name
to this specification in the presence of two sub-
scribing witnesses.

HENRY J. WELDON.
